US00D900868S

(12) **United States Design Patent** (10) **Patent No.:** **US D900,868 S**
Wilde (45) **Date of Patent:** **** Nov. 3, 2020**

(54) **DISPLAY SCREEN WITH GRAPHICAL USER INTERFACE**

(71) Applicant: **Navitaire LLC**, Minneapolis, MN (US)

(72) Inventor: **Justin S. Wilde**, Salt Lake City, UT (US)

(73) Assignee: **Navitaire LLC**, Minneapolis, MN (US)

(**) Term: **15 Years**

(21) Appl. No.: **29/657,336**

(22) Filed: **Jul. 20, 2018**

Related U.S. Application Data

(60) Division of application No. 29/598,035, filed on Mar. 22, 2017, now Pat. No. Des. 835,668, which is a continuation-in-part of application No. 29/595,896, filed on Mar. 2, 2017, now abandoned.

(57) **CLAIM**

The ornamental design for a display screen with graphical user interface, as shown and described.

DESCRIPTION

The sole FIGURE is a front view of a display screen with graphical user interface, showing my new design.

The broken lines of uneven length show the display screen and form no part of the claimed design. The broken lines of even length illustrate portions of the display screen with graphical user interface that form no part of the claimed design.

1 Claim, 1 Drawing Sheet
